REFRIGERATOR CABINET

Richard Bolton Janes, Baldwin Lake, Greenville, and James W. Snider, Buchanan, Mich., assignors to Gibson Refrigerator Company, Greenville, Mich., a corporation of Michigan

Application January 18, 1951, Serial No. 13,858

Term of patent 7 years

(Cl. D67—3)

To all whom it may concern:

Be it known that we, Richard Bolton Janes and James W. Snider, citizens of the United States, residing at Baldwin Lake, Greenville, in the county of Montcalm and State of Michigan, and 304 Days Avenue, Buchanan, in the county of Berrien and State of Michigan, respectively, have invented a new, ornamental, and original Design for a Refrigerator Cabinet, of which the following is a specification, reference being had to the accompanying drawings, forming a part hereof.

In the drawings:

Figure 1 is a perspective view of a refrigerator cabinet, embodying our new design;

Figure 2 is a cross-sectional view of the refrigerator door taken substantially on the line 2—2 of Figure 1;

Figure 3 is a fragmentary side elevational view of the refrigerator; and

Figure 4 is a fragmentary top view of the refrigerator.

The top, back and sides of the refrigerator cabinet are plain.

The dominant features of the design reside in the portion shown in full lines.

We claim:

The ornamental design for a refrigerator cabinet, substantially as shown and described.

RICHARD BOLTON JANES.

JAMES W. SNIDER.
